UNITED STATES PATENT OFFICE.

ANTONIO MUSCARELLA, OF NEW YORK, N. Y.

COMBINATION LOCK-KEY.

1,148,526.

Specification of Letters Patent.

Patented Aug. 3, 1915.

Application filed October 15, 1914. Serial No. 866,745.

To all whom it may concern:

Be it known that I, ANTONIO MUSCARELLA, a subject of the King of Italy, residing at the borough of Manhattan, city, 5 county, and State of New York, have invented certain new and useful Improvements in Combination Lock-Keys, of which the following is a specification, reference being had to the accompanying drawings.

10 This invention relates to improvements in keys for locks and particularly to improvements in permutation or combination lock keys; that is, a lock-key which can be engaged with the lock only after the combination 15 of the key has been solved.

An object of this invention is to provide a lock-key of the class just referred to which will be simple in construction, comparatively cheap in manufacture and efficient in operation and use.

Another object of this invention is to provide a lock-key of the kind just described in which the key may be readily detachable from the other parts of the mechanism, 25 whereby an added safeguard is obtained.

In the drawing illustrating the principle of this invention and the best mode now known to me of applying that principle, Figure 1 is a central vertical section of my new combination lock-key; Fig. 2 is a view looking in the direction of the arrow B of Fig. 1; Fig. 3 is a section on the line A—A of Fig. 1; Fig. 4 is a detail showing the knob-spindle, the key detachably secured thereto and the sleeve mounted on the spindle; Figs. 5, 6 and 7 are an elevation, a side view and a plan, respectively, of the ring-support; Fig. 8 is an elevation of the ring-separator; Fig. 9 is a central vertical section 35 of the ring-separator; Fig. 10 is an elevation of an indicator-ring and a stop-ring mounted therein; Fig. 11 is an elevation of a stop-ring; Fig. 12 is an elevation, partly in section of a modified form of my 40 new lock-key; and Fig. 13 is an elevation of the base-member shown in Fig. 12.

The base-member *a* is cup-shaped and is inserted in a recess *b* formed in the door *c*. This base-member *a* is formed with an annular flange *d* from which projects forwardly a circular series of pins *e*; and near the pins *e* there are inscribed a series of numbers (such as the digits) and a series of letters (as A, B, and so on). In a recess *b'* formed 55 in the side of the door *c* opposite the base-member *a*, there is mounted the lock proper

f, which may be of any suitable type and which is provided with the bolt *g*. By means of screws *h* the lock proper *f* is fastened to the back or bottom *i* of the cup-shaped base-member *a*. This bottom *i* is formed with a recess or depression *j* and with a circular hole *k* near the center of the latter. In this depression *j* there is fitted the rectangular base *m'* of a ring-support *m* having a hollow cylinder or barrel *m''* that projects from the base *m'*. This barrel *m''* is formed with a lengthwise-extending slot *m** and the base *m'* is formed with a recess or notch *m** in line with this slot *m**. One of the walls of the slot *m** is formed with a pair of notches *n*. By means of screws *a'* the base *m* is fastened to the base-member *a*. From the cylindrical surface of the barrel *m''* there project teeth or 60 lugs *o*. The barrel *m''* of the ring-support *m* is adapted to receive the slotted cylindrical portion or barrel *p* of a ring-separator *q*; and from one of the walls *r'* of the slot *r* in the cylindrical part or barrel *p* there project teeth *r* which fit into the notches *n* formed in one of the walls of the slot *m** in the ring-support *m*. The ring-separator *q* is formed with an annular head or flange *q'* which bears against the outer end of the 65 barrel *m''* of the ring-support *m*. In the particular form shown in the drawings, there are provided three indicator rings *s* on the outer cylindrical surface of which are inscribed a series of numerals (as the digits) 70 and a series of letters (as A, B and so on), these numerals and letters corresponding to the numerals and letters inscribed upon the circular flange *d* of the base-member *a*. Each indicator-ring *s* is internally notched, 75 as shown at *s'*; and each notch *s'* is adapted to receive and hold snugly a lug or tooth *t'* projecting from the stop-ring *t*, which is formed with a recess *t''*. These rings *t* are mounted upon the ring-support *m* and normally are held apart or separated by the lugs *o* formed on the latter and by the lugs or teeth *r* which project from the cylindrical part *p* of the ring-separator *q*. To each 80 of the indicator-rings *s* there is fastened a cylinder *u* which conceals and shields the outer cylindrical inscribed surface of the indicator-ring *s*; and each of these rings *u* is provided with a tongue or lip *u'* by means of which the indicator-rings *s* (and the stop-rings *t*) may be turned. The cylindrical part or barrel *p* of the ring-separator *q* 85

forms a bearing for the sleeve member *v* which is formed with a series of teeth *v'* and through which passes the spindle *w* the outer end of which is formed with a 5 knob *x* and the inner end of which is slotted at *y* to receive the butt end of a key *z*.

The sleeve *v* lies between a collar *w'* formed on the spindle *w* and a washer *w''* mounted on the latter; the washer *w''* is 10 held in place by a pin *w''*. The teeth or lugs *v'* lie in a line parallel to the longitudinal axis of the sleeve *v*; and these teeth *v'* are adapted to enter the slot *r''* in the cylindrical part *p* of the ring-separator *q*. Normally the stop-rings *t* prevent the spindle *w* and its attached key *z* from being forced inwardly into engagement with the lock proper *f*; but, when the combination of the lock has 15 been solved and the stop-rings *t* have been turned to their releasing position, the recesses *t''* or notches are in alignment with one another and with the teeth *v'* on the sleeve *v*; hence, in this position of the stop-rings *t*, the spindle *w* and its attached key *z* 20 may be forced inwardly, whereby the key *z* is engaged with the lock *f*. By means of a screw-pin *z'*, the key *z* is held detachably in the slot *y*; and, by loosening this screw-pin *z'*, the key *z* may be readily removed from 25 the slot *y* and taken away by the owner, after which the sleeve *v* and spindle *w* may be replaced. The key *z* is thus made detachable from the spindle *w*; and this is an added safeguard and an important feature of 30 this invention, since the owner of the house can take with him the key *z* and, even if the combination of the lock be solved by a burglar or other would-be intruder, he cannot 35 unlock the door, since the owner has the key 40 with him.

In the modified form shown in Fig. 12, the cup-shaped base-member *a* is dispensed with and there is placed upon the outside of the door a disk-like indicator-plate 2 having a circular series of pins *e* projecting from its face *2'*. This disk 2 is formed with a recess 3 in which fits the rectangular base *m'* of the ring-support *m*; and, by means of screws *h*, the lock proper *f* is fastened to 45 the plate 2 and the rectangular base *m*. Furthermore, the cylinders *u* are omitted in this modification, and L-shaped fingers *u''* are fastened directly to the indicator-rings *s''*. This modified form of my invention is 50 particularly well adapted for use where the wood of the door is thin and does not permit of the formation of a recess *b*, such as is indicated in Fig. 1. The circular series of studs *e* are provided in order that the combination may be readily solved in the dark; that is, for example, in the night time when the characters inscribed on the base-member 55 cannot be seen. When the key *z* is connected with the lock proper *f*, the knob *x* 60 can be used as an ordinary knob.

The operation of the mechanism hereinbefore described will now be readily understood and may be set forth as follows: Assuming that the combination is 2 A 8, one of the ears *u'* is brought into register with 70 the number 2 on the face of the flange *d* (Fig. 2), another of the ears *u'* is brought into register with the letter A and the third of these ears is brought into register with the number 8. By thus setting the ears *u'*, 75 the rings or cylinders *u*, the indicator-rings *s* and the stop-rings *t* are turned and the slots *t''* in the latter are brought into alignment so that the teeth *v'* can without hindrance be pushed therethrough. Hence, the 80 operator now seizes the knob *x* and presses inwardly the sleeve *v* and the spindle *w* and thereby forces the key *z* into the lock proper *f*, which is shown merely conventionally in the drawings and may be of any ordinary 85 construction. By turning the knob *x* the bit *z''* of the key *z* is made to actuate the mechanism (not shown) of the lock *f* and thereby to withdraw the bolt *g* thereof, as will be understood readily by all skilled in this art. 90

I claim:

1. A permutation lock-key comprising a ring-support formed with lugs and with a slot one wall of which is formed with recesses; a slotted ring-separator mounted in 95 said ring-support and formed with teeth which engage in said recesses; apertured stop-rings mounted on said ring-support and separated by said teeth and lugs; indicator-rings within which said stop-rings are 100 carried; a lock-operating spindle; and a sleeve mounted on said spindle and formed with teeth adapted to pass through the apertures in said stop-rings when said apertures are brought into alignment. 105

2. A permutation lock-key comprising a ring-support; apertured stop-rings mounted on said ring-support; means for holding said stop-rings separated from one another; a lock-operating spindle; and a sleeve loosely 110 mounted on said spindle and formed with teeth adapted to pass through the apertures in said stop-rings, when said apertures are brought into alignment.

3. The combination with a lock proper; of a permutation lock-key including a spindle; a key fitted to said lock and carried by said spindle, said key being readily detachable from the latter; and permutation devices for preventing said spindle to be 115 moved to bring said key into operative engagement with said lock. 120

4. A permutation lock-key comprising a ring-support; a base-member in which said ring-support is carried and on which are inscribed suitable characters; apertured rings mounted on said ring-support and bearing characters corresponding to the characters inscribed on said base-member; rings which shield from view the characters 125 130

on said rings; a lock-operating device; and a sleeve mounted on said device and formed with teeth adapted to pass through the apertures in the first-named rings, when the 5 apertures therein are brought into alignment.

5. The combination with a lock proper; of a permutation lock-key comprising a base-member fastened to the lock proper; a 10 ring-support carried by said base-member; a lock-operating device; and rings mounted on said ring-support and arranged normally to prevent the engagement of said device with the lock proper.
- 15 6. The combination with a lock proper; of a permutation lock-key comprising a base-member fastened to the lock proper; a

ring-support carried by said base-member; a longitudinally-movable spindle; a key fitted to the lock proper and detachably fastened to said spindle; and rings mounted on said ring-support and arranged normally to prevent the engagement of said key with the lock proper.

In testimony whereof I have hereunto set 20 my hand at the borough of Manhattan, city, county and State of New York, this 8th day of October, A. D., 1914, in the presence of the two undersigned witnesses.

ANTONIO MUSCARELLA.
